UNITED STATES PATENT OFFICE.

WILLIAM HENRY SHERROD, OF SEATTLE, WASHINGTON, ASSIGNOR TO JAMES HENRY SHARPE, OF SAN FRANCISCO, CALIFORNIA.

LENS FOR AUTOMOBILE-HEADLIGHTS.

1,323,993.

Specification of Letters Patent.

Patented Dec. 2, 1919.

Application filed February 21, 1918. Serial No. 218,577.

To all whom it may concern:

Be it known that I, WILLIAM HENRY SHERROD, a citizen of the United States, residing at Seattle, in the county of King and

5 State of Washington, have invented a new and useful Improvement in Lenses for Automobile-Headlights, of which the following is a specification.

This invention relates to improvements 10 in lenses for use in the front lamps of motor driven vehicles, and the object of this improvement is to produce a lens comprising a series of prisms, certain of which prisms refracted to project the light emerging 15 from the head lamp downwardly in the roadway and thus do away with the blinding glare that is always visible to pedestrians and to the driver of an approaching car, without sacrificing any material part 20 of the illuminating efficiency of the headlight.

A further object resides in the provision of certain prisms for projecting the rays downwardly with a wider beam in front of 25 the car, and a still further and all important object resides in the provision of a lens having prisms laterally disposed and of such refraction as to project intersecting rays for lighting both sides of the roadway.

30 The advantages of direct prismatic projection of the light rays over prismatic diffusion thereof is twofold. In the first place, prismatic diffusion impairs the illuminating qualities of the cone of rays; and secondly, such light as may be reflected to the side of the car by the diffused rays does not illuminate sufficiently or carry far enough to be of any material advantage, as, for instance, in rounding an abrupt curve in the 40 roadway.

My invention contemplates certain distinct projections of the light rays, a more detailed explanation of which will be found in the following specification, illustrated in 45 the accompanying drawings, and finally pointed out in the appended claim.

In the drawings Figure 1 is a plan view 50 of my improved lens; Fig. 2 is a side elevation thereof; Fig. 3 is a section cut along line A—A of Fig. 2; and Fig. 4 is a section cut along line B—B of Fig. 2.

Referring more particularly to the drawings, in which like reference numerals indicate like parts, the numeral 2 represents 55 the cylindrically shaped flange provided on

the peripheral edge of my integrally formed lens, which is adapted to be disposed within an ordinary socket provided in an automobile lamp.

12 is a prism comprising substantially the 60 upper half area of the lens and being of greater thickness at its lower edge 4 and tapering toward its upper edge as at 3, so that it will have the effect of projecting downwardly the rays of light that pass 65 therethrough.

The lower prism 14 of the lens being of decreasing thickness from the lower center portion of its periphery 7 to its upper periphery 8 thus increases the projection of 70 the cone of rays downwardly so that the beam of illumination will appear directly in front of the car upon the roadbed.

13 and 15 are integrally formed prisms disposed on the adjacent sides of the lower 75 half section of the lens and these prisms are correspondingly of decreasing thickness from their outer peripheral edges to their adjacent disposed apexes 5', where they converge to a point of contact in the center 80 of the lens.

The advantages that inure from the decreasing thickness of these two laterally disposed converging prisms are first, that no light rays from the center portion of the lens 85 will be refracted laterally but will be bent downwardly to illuminate the road ahead of the vehicle, and secondly, such rays as emerge are caused to be projected laterally and downwardly to light a considerable area 90 on both sides of the car. I thus attain through the angular relationship of these four prisms separate and distinctive rays of light projection, as, for instance, the cones of rays emerging from the upper and 95 lower prisms are projected outwardly below the horizontal and downwardly to illuminate the roadway, and the two adjacent laterally disposed prisms project the cones of rays laterally and downwardly to illuminate 100 the area on both sides of the car.

The outside surfaces of the prisms 12, 13, 14 and 15 are all disposed in the same parallel plane and the inside surfaces are all disposed at an angle to the outside surfaces 105 so that they will deflect the rays of light that pass therethrough.

Having thus described my invention, what I claim as new and desire to protect by Letters Patent, is:

A lens comprising a plurality of prismatic sections on its rear face, one of said sections comprising the upper half area of said lens and being of decreasing thickness from 5 its lower horizontal edge to its upper periphery, laterally disposed prismatic sections of decreasing thickness from their outer peripheral edges to their horizontally disposed apexes, and the lower prismatic

section being correspondingly of decreasing thickness from its lower to its upper periphery.

Signed by me at Seattle, Washington, this 4th day of February, 1918.

WILLIAM HENRY SHERROD.
